UNITED STATES PATENT OFFICE.

HARRY A. BAUMAN AND ROBERT M. PIERSON, OF AKRON, OHIO, ASSIGNEES TO THE B. F. GOODRICH COMPANY, OF NEW YORK, N. Y., A CORPORATION OF NEW YORK.

DESIGN FOR A BATHING CAP.

Application filed April 4, 1927. Serial No. 21,456. Term of patent 14 years.

To all whom it may concern:

Be it known that we, HARRY A. BAUMAN and ROBERT M. PIERSON, citizens of the United States, residing at Akron, in the county of Summit, and State of Ohio, have invented a new, original, and ornamental Design for Bathing Caps, of which the following is a specification, reference being had to the accompanying drawing, forming a part thereof.

Fig. 1 is a side elevation of a bathing cap showing our new design.

Fig. 2 is a substantially vertical section of one wall thereof on the line 2—2 of Fig. 1.

We claim:

The ornamental design for a bathing cap as shown.

HARRY A. BAUMAN.
ROBERT M. PIERSON.
